UNITED STATES PATENT OFFICE.

JOHN G. BLESSING, OF CHICAGO, ILLINOIS, ASSIGNOR TO JOSEPH E. COCHRAN, OF CHICAGO, ILLINOIS.

WEIGHING-SCALE.

No. 821,278.

Specification of Letters Patent.

Patented May 22, 1906.

Application filed March 18, 1905. Serial No. 250,816.

To all whom it may concern:

Be it known that I, JOHN G. BLESSING, a citizen of the United States, residing at Chicago, in the county of Cook and State of Illinois, have invented a certain new and useful Improvement in Weighing-Scales, of which the following is a specification.

My invention relates to weighing-scales; and the objects of the invention are, first, to improve the construction and mounting of the dial, and, second, to provide means for overcoming backlash between the dial-shaft bevel-gear and the bevel-gear in mesh therewith. The means shown for overcoming backlash between the scale-beam rack and its pinion I do not claim, as I am not the inventor thereof.

I attain my objects by the mechanism illustrated in the accompanying drawings, in which—

Figure 1 is a side elevation of the complete scale, part being shown in section to reveal the interior mechanism. Fig. 2 is a plan view of the complete scale. Fig. 3 is a transverse sectional view taken on line 3 3, Fig. 1. Fig. 4 is a perspective view of the yoke wherein one of the bevel-gears is mounted. Figs. 5 and 6 are side and plan views, respectively, of the gears by which the motion of the scale-beam is transmitted to the dial-shaft. Fig. 7 is a face view of the preferred form of reading member. Fig. 8 is a general side view of the conical dial. Fig. 9 is a fragmentary development of the dial, drawn to an increased scale, illustrating the preferred arrangement of the dial-numbers. Fig. 10 is a fragmentary detail view showing the construction of the guard for preventing the pivoted rack from becoming unmeshed from its pinion.

Similar letters refer to similar parts throughout the several views.

The scale-beam *a* is fulcrumed upon the post *b* of the main frame *b* and carries at one extremity the scale-pan *c* and at the opposite extremity means for transmitting motion to the dial-shaft. In the preferred construction here shown the transmitting means consists of a rack *d*, which is pivoted to the extremity of the scale-beam and conforms to the arc of a circle having as a radius the distance between the scale-beam fulcrum and the point of attachment of said rack to the scale-beam. Said rack is adapted to mesh with the pinion

e, rotatably mounted in yoke *f*, as best shown in Figs. 5 and 6, and in order that said rack may at all times tend to approach said pinion to make close contact therewith and avoid backlash it is desirable to provide said rack *d* with a weighted arm *d'*, extending approximately at right angles to said rack, as best shown in Fig. 1. With this form of rack a stationary guard or keeper *d''* should be provided for preventing said rack *d* from becoming unmeshed from pinion *e*.

The rotation of pinion *e* is transmitted to the vertical dial-shaft *g* by means of the bevel-gear *e'*, which has a horizontal axis and is adapted to mesh with the bevel-gear *g'*, rigidly secured to said dial-shaft *g*. In the preferred construction in order to reduce as far as possible the number of parts in the device the pinion *e* and bevel-gear *e'* are integral with each other and rotatably mounted upon shaft *f'*, mounted in the yoke *f*.

For the purpose of avoiding as far as possible backlash between gears *e'* and *g'* gear *e'* is made vertically movable, is placed above gear *g'*, and is weighted to tend to settle down into close contact therewith. The construction whereby this result is obtained is best illustrated in Figs. 1, 4, 5, and 6, wherein yoke *f*, which carries the gears *e'*, is shown to be pivoted to the stationary horizontal pin *b''*, rigidly secured to a wall of the frame *b*. Said yoke is preferably U-shaped, as shown, and a weight *f''* is carried upon an extension of said yoke at a point away from pin *b''* beyond shaft *f'*. By this construction the weight of yoke *f* and parts mounted thereon tends to force the gears *e'* and *g'* more closely together. Gear-teeth, especially involute teeth, which are the kind preferred in this device, are wider at the base than at the crown, and by forcing gear-wheels of this kind together the teeth will become wedged together, so as to make direct contact with each without any appreciable lost motion or backlash. By thus holding the gear *e'* close to gear *g'* backlash will be avoided and the dial-shaft *g* and dial thereon will be brought to rest in an absolutely correct position.

By referring to Figs. 1 and 3, it will be seen that while the rack *d* is driving pinion *e* it has a tendency to raise gear *e'* away from gear *g'*. The result will be that during rotation said gears will mesh loosely and the friction be-

tween them will be reduced to a minimum; but as soon as the rack d and gear e' have ceased to rotate the latter will, acting under its own weight augmented by that of the 5 yoke f'' and weight f^2 thereon, tend to settle down into close contact with gear g' and bring the latter accurately to rest. A stoppin b^3 is rigidly secured to main frame b or other stationary part of the machine in such 10 position as to limit the upward swing of yoke f about its pivot b^2 . This will prevent the unmeshing of gear e' from gear g' .

The dial-shaft g above mentioned is arranged vertically and at its lower extremity 15 has a step-bearing b^4 , secured in stationary position upon main frame b . Rigidly secured to shaft g at the upper portion thereof is the conical dial h , which is concentric with shaft g and bears upon its surface a series of 20 numbers concentrically arranged. These numbers represent products adapted to be read in connection with a stationary reading member i . Scales of this type are primarily intended to be used as computing-scales by 25 grocers and other retail merchants, and it is common custom to employ scales having two faces or dials, one of which may be read by the customer to show the number of pounds' weight of the article, the other to be read by 30 the merchant to show the total amount in dollars and cents to which the article comes at a given price per pound. In my scale it is contemplated that the reading member i shall lie upon the side occupied by the merchant; but it is to be noted that by my construction, in which the dial is conical, the same dial may be employed for both indicating the total amount in money to the merchant and simultaneously the total weight to 35 the customer who is on the opposite side of the scale. To render this practicable, two series of numbers h' and h^2 are employed. The series h' are product-numbers, intended to be read from the merchant's side and representing the total monetary amount of the purchase. These numbers are arranged in circles having the axis of the conical dial as a 40 center and are adapted to be read in connection with said reading member i , which bears 45 multiplier or "price per pound" numbers in the manner hereinafter described. The series of numbers h^2 represent pounds' weight and are intended to be read from the customer's side of the scale. These numbers 50 will run from zero up and are also arranged in a circle concentric with the axis of the dial, but preferably are located at the lower peripheral edge of the dial, as indicated in Fig. 8. As the two sets of numbers h' and h^2 are 55 to be read from opposite sides of the scale, the zero-points of the two sets will lie on diametrically opposite sides of the dial. It is 60 desirable that the merchant should also be

able to read the pounds' weight, and for this purpose a second row of numbers h^3 is marked 65 upon the dial in a circle just above the numbers h^2 . The zero-point will correspond with the zero-point of the numbers h' .

Ordinarily it is impractical and unnecessary to print upon the dial a separate product-number to represent each cent, and a common custom is to print a number for each five cents or ten cents and represent the intermediate cents by dots or short radial lines. In Fig. 9 I have shown a dial-marking which 70 may be employed in connection with my dial, if desired. By this arrangement every tenth cent in any given row has a printed number representing it and also a comparatively heavy radial line. A fainter radial line is 75 placed midway between each tenth-cent line, and five dots are placed at equal distances between each fifth-cent line. This in itself is not new; but I propose when desired to arrange the dots between any two fifth-cent 80 lines obliquely for rendering each dot more distinctive to thereby increase the ease with which the dial may be read.

The reading member i hereinabove referred to consists, preferably, of a strip of glass 85 having a reading-line i' extending lengthwise thereof for constituting a line of sight along which the dial-numbers may be read. It is desirable in order to avoid parallax in 90 reading to etch or otherwise mark the reading-line upon the under side of the glass strip and to mount said strip as close as possible to dial h , leaving just sufficient space to clear it as it rotates. On member i at the side of 95 said reading-line are marked multiplier or 100 price numbers, one for each row of product-numbers on the dial after the usual manner in computing-scales.

In the preferred construction a conical cap j , conforming closely to the shape of h , is 105 placed over said dial and rigidly secured to framework b . Such a cap both affords protection to said dial and serves as a support for the reading member i . It is desirable that said cap be opaque and consist, for example, of enameled sheet metal. In such case a slot j' will be formed in said cap at the point where the reading-number is to be placed. Said slot is of sufficient length to exhibit all the product-numbers h' , but not 110 the weight-numbers h^2 , which latter are here shown to be located at or near the lower edge of the dial. In order to exhibit said weight-numbers on the side opposite to the reading-number i , a second slot j^2 is formed in said cap 115 at the proper height to exhibit said weight-numbers without exhibiting said product-numbers.

In operation when an article to be weighed 120 is placed upon the scale the opposite extremity of the scale-beam a will be raised, thus

causing rack d to rotate pinion e and gear e' . The upward movement of said rack d will tend to raise said pinion e and lift the gear e' slightly away from its companion gear g' , this motion being permitted by the pivotal mounting of yoke f , but being limited by the stoppin b^3 . This elevating of gear e' permits the gears to run loosely with a minimum amount of friction, and the rotation of gear g' will cause the rotation of shaft g and dial h . As soon as pinion e has been rotated the proper amount it will, acting under gravity, settle down into close contact with gear g' , and thereby bring said gear and the dial accurately to position. In consequence the rotation of the gears will be free and yet when the rotation is complete the dial will be in correct position.

There is another important advantage mechanically in mounting the conical dial upon a vertical shaft, for with such construction the dial, if accurately formed is always "in balance." Consequently friction upon the bearings and eccentricity due to inequality of weight will be avoided. There is another and minor advantage in employing a vertical shaft and that is that a jeweled step-bearing may be employed which operates practically without friction and without wear and without the necessity of lubrication. There are two other important advantages in employing a conical dial in the manner shown, and these are, first, that the same dial may be read simultaneously from opposite sides of the scale, and, second, that a greater surface is afforded for the numbers than would be afforded by a flat dial of the same exterior diameter. In connection with the latter feature it will be understood that in computing dials of this general class there is a separate row of product-numbers h' for each multiplier or price per pound. In order, therefore, to give a wide range of prices, it becomes necessary to employ a very large dial or sacrifice the size of the numbers. By employing a conical dial the superficial surface is increased, and a greater number of rows h' may be employed with the same external diameter and the same sized numbers.

I do not desire to be limited to the specific form of cap here shown, as it is not necessary that such cap should completely inclose the dial, nor do I desire to be limited to the precise arrangement of the figures upon dial h , nor to the precise manner of mounting shaft g . It is obvious that the constructions may be considerably varied without departing from the spirit of my invention.

Although I have shown the cone to be produced to a point, this is not essential, as any right frustum of a cone would operate upon the same principle.

Attention is hereby directed to my com-

panion application for weighing-scales, filed by me on even date herewith, Serial No. 65 250,817.

What I claim as new, and desire to secure by Letters Patent, is—

1. In a weighing-scale the combination with the scale-beam and beam-support of a 70 rotatable dial having a conical exterior surface with product-numbers arranged in concentric rows thereon, a stationary reading member adjacent to said dial, a shaft whereto said dial is secured; a bevel gear-wheel fastened to said shaft for rotating it, and a second bevel gear-wheel adapted to mesh with the first, said second gear-wheel being bodily movable toward and from the first and being weight-influenced to approach it, said bodily- 75 movable gear-wheel being driven from the scale-beam.

2. In a weighing-scale, the combination, with the scale-beam, beam-support and a 80 reading member, of a dial rotatable about a vertical axis and operated by the scale-beam, said dial having product-numbers arranged in concentric rows thereon and having a conical exterior surface, a vertical shaft whereto said dial is secured, and a pair of intermeshing bevel-gears, one of which rotates said shaft and the other of which is rotated by the scale-beam, one of said gears being restrained from moving in an axial direction and the other being movable and weight-influenced to approach the first to thereby bring the dial to rest in correct position. 85

3. In a weighing-scale, the combination, with the scale-beam and beam-support, of a 90 rotatable dial; means for reading said dial; a 100 shaft whereon said dial is mounted; and a pair of intermeshing bevel-gears for rotating said dial, one of said bevel-gears being rigid on said shaft and the other being vertically movable and weight-influenced to approach the first 105 for bringing the dial to rest in correct position, the vertically-movable bevel-gear being driven from the scale-beam.

4. In a weighing-scale, the combination, with the scale-beam and beam-support, of a 110 rotatable dial; means for reading said dial; a 115 shaft whereon said dial is mounted; and a pair of intermeshing bevel-gears, one of which rotates said shaft and the other of which is rotated by the scale-beam, one of said gears being restrained from moving in an axial direction and the other being movable and weight-influenced to approach the first to thereby bring the dial to rest in correct position.

5. In a weighing-scale, the combination, 120 with the scale-beam and beam-support, of a rotatable dial; means for reading said dial; a 125 shaft whereon said dial is mounted; and a pair of intermeshing bevel-gears for rotating said dial, one of said bevel-gears being rigid on said shaft, a pivotally-supported member wherein

the other of said bevel-gears is mounted; said member being weighted for bringing its bevel-gear more closely into contact with the other bevel-gear; and gear connections between 5 said movable bevel-gear and the scale-beam whereby the motion of said beam is imparted to the movable bevel-gear.

In witness whereof I have hereunto subscribed my name in the presence of two witnesses.

JOHN G. BLESSING.
